UNITED STATES PATENT OFFICE.

RALPH V. SAGE, OF WESTMONT, PENNSYLVANIA.

DUMPING-CAR.

1,083,563.

Specification of Letters Patent.

Patented Jan. 6, 1914.

Application filed August 29, 1912. Serial No. 717,709.

To all whom it may concern:

Be it known that I, RALPH V. SAGE, a citizen of the United States, residing in the borough of Westmont, in the county of Cambria and State of Pennsylvania, have invented certain new and useful Improvements in Dumping-Cars; and I do hereby declare the following to be a full, clear, and exact description of the invention, such as will enable others skilled in the art to which it appertains to make and use the same.

My invention relates to dumping cars with special reference to door-operating and locking mechanism for gondola flat-bottom cars, provided with flush doors, or for other dumping cars, and its object is to provide apparatus of the class described, which is simple of construction, cheap, convenient of operation and easily repaired.

Another object of my invention is to provide mechanism whereby a car-door is held in a closed position by means independent of the lifting connections in case the lifting means should break or become loosened.

To this end the invention consists, generally stated, of a lifting shaft connected to the door, and independent door-locking means operated both for locking and unlocking from the lifting shaft.

In the accompanying drawings forming part of this specification and in which similar characters refer to corresponding parts:—Figure 1 is a vertical transverse section taken on the line I—I of Fig. 2 through a portion of a car body. Fig. 2 is a side elevation of my door operating and locking mechanism, as applied to a flush bottom gondola car.

For the sake of illustration, I have shown my improvement in connection with a flat bottom or gondola car, but the same can be used with a hopper bottom car or any other car with slight modifications, without departing from the spirit and essence of my invention.

Referring to the various characters of reference upon the drawings:—1 designates the lifting or operating shaft which, as shown, extends longitudinally of the car and is mounted in the outer ends of the flying transoms which may either be composed of rolled channels 2, or they may be made of pressed metal as shown at 3. These flying transoms are riveted to the center sills 4 at their inner ends by means of angular brackets 5, if they are rolled shaped, or, if they are

integrally formed of pressed metal, they are riveted directly to the center sills through their inner flanges. The outer ends of the flying transoms are shown riveted directly to the lower ends of the side stakes of the car. These stakes may be rolled sections of angular form, as shown at 6, or they may be of pressed metal, or of any other rolled or pressed shapes, if desired.

The corner shedding plate 7 has its upper flange 8 attached to the lower edge of the side plate of the car and has a lower vertical flange 9 which forms the jamb of the door. This flange 9 may be bent inwardly, if desired, as shown in dotted lines in Fig. 1, so that the door will close against it.

The car-door 10 is hinged at 11 on its inner side to the center sills 4, and is operated by means of the door-operating mechanism comprising the operating shaft 1 which has a worm or winding-drum 12 mounted thereon, connected to the door bracket 13 by suitable lifting means such as a chain 14 or other flexible connection, which is arranged to wind or unwind upon a worm or barrel 12.

The rotation of the shaft in one direction winds up the chain and closes the door, or, if rotated in the opposite direction, the chain unwinds and opens the door.

In order to lock the door in its closed position and to take the strain from the lifting chains and prevent the door from accidentally opening, I provide one or more latches or bolts 15 mounted to slide in suitable bearings or hangers 16, secured to the lower face of the door and arranged to be projected outwardly beyond the edge of the door by means of a spring 17 and, when the door is closed, engage the cylindrical surface of a tappet 18 which is mounted on the operating shaft 1 and comprised of an annular sleeve and projection as shown.

In the bottom of each of the hangers 16 is a slot 19 in which is mounted a pin 20 secured to the latch 15 to limit its movement. Another perforation 21 at the end of the hanger is to allow the escape of air or any foreign material which would prevent the free movement of the latch.

A wearing plate 22 is secured to the car-door within the hangers between the hangers and the door, upon which the latch plays.

The operation of the device is as follows:—Assuming that the door is closed, as shown in full lines in the drawings:—In

order to release the car-door, the operating shaft 1 is turned in the direction of the arrow shown in Fig. 1, and in doing so the straight face of the tappet 18 comes in contact with the end of the latch 15 pushing it backward beyond the cylindrical surface of the tappet and releasing the door. At the same time the chain will be unwound and the door will swing downwardly and inwardly to its open position. In closing the door the operating shaft is turned in the reverse direction, which will wind up the chain, and, owing to the rounded end of the latch, it will be pushed back when it comes to the cylindrical surface of the tappet, and after passing the same, the latch will assume the position shown in full lines in Fig. 1, whereby the weight of the door at that side will be sustained by the operating shaft.

Although the shaft is shown as extending longitudinally of the car, it may be located transversely, inclined, or in any suitable position, as will be understood by those skilled in this art.

While I have shown and described my invention in considerable detail, I do not wish to be limited to the exact details of construction specified, but may use such substitutions, modifications or alterations as fall within the scope of my invention and as pointed out in the claims.

Having thus described my invention, what I claim and desire to secure by Letters Patent is:—

1. The combination with a hinged car-door, of an operating shaft mounted on the car body, flexible connections therefrom to the door, a spring projected locking mechanism independently mounted on said door retracted and supported by the said operating shaft, arranged to support the door in its closed position.

2. The combination with a hinged car-door, of an operating shaft mounted on the car body, flexible connections therefrom to the door, a spring-projected latch retracted and supported by the said operating shaft and independently mounted on said door and arranged to lock the same in its closed position.

3. The combination with a hinged car-door, of an operating shaft mounted on the car body, flexible connections therefrom to the door, a spring-projected latch independently mounted on the door for locking the door and supporting same on said shaft, and means on the operating shaft for retracting said latch.

4. The combination with a hinged car-door, of an operating shaft mounted on the car body, flexible connections therefrom to the door, a spring projected latch independently mounted on the door adapted to lock the door in its closed position and support

the same on said shaft, and means on the operating shaft for retracting said latch by the opening movement of said shaft.

5. The combination with a hinged car-door, of an operating shaft mounted on the car body, flexible connections therefrom to the door, a latch mounted on the door adapted to lock the door and support the same on said shaft in its closed position, a spring for normally keeping the latch projected, a tappet mounted on the operating shaft and adapted to engage the latch and retract the same by the opening rotation of said shaft.

6. The combination with a hinged car-door, of an operating shaft, flexible connections therefrom to the door, a latch attached to the door, means for guiding the latch, and a spring for normally keeping the latch projected and bearing on the operating-shaft when the door is closed.

7. The combination with a hinged car-door, of an operating shaft, flexible connections therefrom to the door, a latch attached to the door, a spring for normally keeping the latch projected beyond the door, said latch bearing on the operating shaft when the door is closed, and a tappet mounted on the operating shaft adapted to release the latch by the opening rotation of said shaft.

8. The combination with a hinged car-door, of an operating shaft, flexible connections therefrom to the door, a latch attached to the door, a spring for normally keeping the latch projected beyond the door, said latch bearing on the operating shaft when the door is closed, and means mounted on the operating shaft for releasing the latch by the opening rotation of said shaft.

9. The combination with a hinged car-door, of an operating shaft mounted on the car body, a chain connecting the door with the operating shaft and a spring pressed latch secured to the door and bearing on the operating shaft when the door is closed.

10. The combination with a hinged car-door, of an operating shaft mounted on the car body, a chain connecting the door with the operating shaft, a spring pressed latch secured to the door and bearing on the operating shaft when the door is closed, and a tappet mounted on the operating shaft adapted to release the latch by the opening rotation of said shaft.

11. The combination with a hinged car-door, of an operating shaft mounted on the car body, a chain connecting the door with the operating shaft, a spring pressed latch secured to the door adapted to bear on the operating shaft, a tappet mounted on the operating shaft and adapted to release said latch by the opening rotation of said shaft.

12. The combination with a hinged car-door, of an operating shaft mounted on the car body and provided with a tappet mounted thereon, a chain connecting the door with

the operating shaft, a spring actuated latch mounted on said door and having its end adapted to bear on the sleeve of the tappet aforesaid.

- 5 13. The combination with a hinged car door, of an operating shaft mounted on the car body, a tappet mounted on said shaft, a chain connecting the door with the operating shaft, a spring actuated latch mounted on 10 the door, having its ends adapted to bear on the cylindrical portion of said tappet, said tappet being adapted to release the latch by the rotation of the operating shaft when rotated in the direction for opening the door.
- 15 14. The combination with a hinged car door, of an operating shaft mounted on the

car body, flexible connection therefrom to the door, a latch mounted on the door adapted to lock the same in its closed position, means mounted on the door for guiding the 20 latch, a spring mounted thereon adapted to normally keep the latch projected, a tappet on the operating shaft and adapted to engage the latch and to retract the same when the operating shaft is revolved to open the 25 door.

In testimony whereof I hereto affix my signature in the presence of two witnesses.

RALPH V. SAGE.
